UNITED STATES PATENT OFFICE.

SEYMOUR W. PEREGRINE, OF GRAND RAPIDS, MICHIGAN, ASSIGNOR TO
CHARLES J. REED, OF NEW YORK, N. Y.

SCHOOL SEAT AND DESK.

SPECIFICATION forming part of Letters Patent No. 635,584, dated October 24, 1899.

Application filed January 3, 1898. Serial No. 665,281. (No model.)

To all whom it may concern:

Be it known that I, SEYMOUR W. PEREGRINE, a citizen of the United States, residing at the city of Grand Rapids, in the county of Kent and State of Michigan, have invented 5 certain new and useful Improvements in School Seats and Desks, of which the following is a specification.

This invention relates to certain new and 10 useful improvements in school seats and desks having the seat and desk substantially vertically adjustable upon a stationary standard; and the objects of the invention are, first, to adjust the seat and desk independently by 15 means of the same adjusting mechanism, which mechanism is adapted to raise and lower the seat when shifted in one direction and to raise and lower the desk when shifted in the opposite direction; second, to adapt 20 the seat and desk to be adjusted independently, so that either the seat or desk may be adjusted without disturbing the occupant; third, to furnish a simple and efficient adjustment for adjusting the seat and desk independently, and, fourth, other objects particularly described and pointed out in the 25 specification and claims. These objects I accomplish by means of the mechanism illustrated in the accompanying drawings, in 30 which—

Figure 1 shows a perspective view of the seat and desk complete. Fig. 2 shows in perspective the seat, the standard, and the desk separated, and also shows the clamping-rod 35 which attaches the desk to the standard. Fig. 3 shows a plan view of the adjusting mechanism with a section of the seat-back, the dotted lines showing the position of the adjusting-rod and its connections when shifted 40 to operate upon the desk. Fig. 4 shows a rear elevation of the adjusting mechanism. Fig. 5 shows an end view of the adjusting mechanism. Fig. 6 shows a modified form of the adjusting-lever when constructed so as to 45 throw the adjusting mechanism into engagement either with the front or rear object, operating the same from one side of the desk. Fig. 7 is a central longitudinal section of a desk and seat made in accordance with my 50 invention.

Similar numerals refer to similar parts throughout the several views.

1 1 show the standards, which are usually constructed of cast-iron, but may be of any other suitable material.

55

2 shows the seat proper, and 3 shows the seat-back. The seat and back may be constructed in any suitable manner.

4 shows the top of the desk.

5 5 show the desk-guide, which is adapted 60 to slide in guides or grooves shown by 6.

In Fig. 3 the numerals 8 and 9 indicate two half-nuts, Figs. 1 and 2 being on such a scale as to show said parts less clearly. The half-nut 8 is attached to the desk-guides, and 9 is 65 attached to the seat-back.

11 11 show adjusting screw-rods, which are shifted at will so as to engage either with the half-nuts 8 or the half-nuts 9.

13 13 are gears, one on each of the adjusting-rods 11.

14 14 are gears rigid with the shaft 17.

15 15 are horizontal slots in the desk adapted to receive the clamping-rod 22, said rod 22 passing through the slots and the slots allowing a horizontal adjustment in order to retain 75 the desk in proper relationship to the seat-back 3.

16 is a device for retaining and limiting the swinging motion of the lever 19, said lever 19 80 being attached to the support of the adjusting-shaft 17 and also adjusting-rods 11 11. The part designated 16 is a quadrant, and the lever 19 rests against its face and is adapted to move along the same. The quadrant is 85 provided with two retaining-notches, Fig. 5, one at each end, with which the lever 19 engages, said notches limiting its stroke or swing.

18 is a notch in the end of the shaft 17, adapted to engage with a suitable wrench or 90 other means used in turning the shaft 17, together with the rigid gears 14 14, which operate through the gears 13 13 the adjusting screw-rods 11 11. Instead of using the notch 18 the end of the shaft may be constructed in 95 any suitable form to engage with the wrench or other device suitable for operating the same.

20 20 are the fulcrum-pivots for the lever 19 in my preferred form. In the modified form 100

shown in Fig. 6 the rod 7 is supported in a suitable bearing on the standard and serves as the fulcrum for operating the shifting mechanism.

5 21^a shows the point of attachment between the lever 19 and the shaft-support 26.

22 shows a clamping-rod adapted to pass through the slots 15 15 and secured in position by means of any suitable nut or other 10 means for the purpose of retaining the desk in position and allowing its horizontal adjustment.

23 is a slot in the standard, with which the clamping-rod 22 engages.

15 25 25 are slots in the seat-frame, through which pass bolts securing the seat to the standard and which allow for the vertical adjustment of the seat independent of the standard.

27 is a clamping-rod which passes through 20 the slots 25.

28 is a foot-guard secured to the standard and constructed in the ordinary manner.

29 is the seat-bracket which supports the seat proper.

25 30 is an opening in the standard, through which the adjusting-shaft 17 passes.

31 is a slot in the standard, through which the end of the shaft-support 26 passes and in which it is adapted to move. The shaft 17, being 30 retained in position in the elongated slot 30 by this adjustment, is adapted to all kinds of combined seats and desks in which the seat and desk are adjusted separately.

The operation of my invention is as follows:

35 When the lever 19 is shifted into the position shown in Fig. 1, the adjusting screw-rods 11 11 are in engagement with the half-nuts 9 9, as shown in Fig. 3. By revolving the shaft 17 to the right the screw-rods 11 11 operate to

40 raise the seat. By reversing the motion of the shaft 17 the movement of the screw-rods 11 11 is reversed and the seat is lowered. The raising and lowering of the seat do not in any way affect the desk, which remains sta-

45 tionary. In order to adjust the desk, the lever 19 is thrown in the opposite direction, which will shift the shaft 17 and its gears 16, together with the screw-rods 11 11 and their attached gears, as shown in Figs. 3 and 5,

50 whereby to cause the said screw-rods 11 11 to engage with the half-nuts 8 8, and said half-nuts being rigidly connected to the desk-guides by revolving the shaft 17 in one direction the desk is raised, and by reversing the

55 motion of the shaft 17 the desk is lowered. The adjustment of the desk either up or down does not in any way affect the movement of the seat. By this construction the same adjusting device, by merely shifting it from its

60 engagement with the desk, operates the desk, and by shifting it into engagement with the

seat operates the seat, thereby greatly simplifying the construction and operation of the parts necessary to adjusting the seat and desk independently of each other.

65

Having thus described my invention, what I claim to have invented, and desire to secure by Letters Patent, is—

1. In a combined school seat and desk, the combination with the standard adapted to support the seat and desk, a seat adjustably supported by the standard, a desk adjustably supported by the standard, suitable adjusting mechanism adapted to raise and lower the seat when shifted into engagement therewith, 75 and to raise and lower the desk when shifted into engagement with said desk and suitable means for shifting said mechanism, said seat and desk being adjustable independently of each other.

80

2. The combination of the standard, the seat, the desk, said seat and desk being adjustably attached to the standard, a shaft provided with gears, screw-adjusting rods also provided with gears engaging with the gears 85 upon the shaft, and suitable mechanism for shifting the shaft, gears and adjusting-rods into operative connection with the seat for the purpose of adjusting the seat vertically, and for shifting them from operative connection with the seat to operative connection with the desk for the purpose of adjusting the desk separately, substantially as described.

80

3. In a school-seat, the combination with the standard, of a shaft extending trans- 95 versely across the standard, gears rigidly connected with said shaft, shiftable screw-rods provided with gears coöperating with gears on the shaft and also with suitable mechanism upon the seat and desk respectively for 100 the purpose of raising and lowering either the desk or seat and means for shifting said screw-rods, substantially as described.

95

4. In combination with the standard, a seat and desk adjustably connected thereto, a shaft 105 extending transversely the seat and desk, gears upon said shaft, adjusting screw-threaded rods having gears engaging with the gears on the shaft, half-nuts upon the seat, and half-nuts upon the standard, and suitable means 110 for shifting said adjusting screw-rods into engagement either with the half-nuts upon the seat or the half-nuts upon the desk, substantially as and for the purpose described.

105

In witness whereof I have hereunto set my 115 hand and seal in the presence of two witnesses.

SEYMOUR W. PEREGRINE. [L.S.]
